UNITED STATES PATENT OFFICE.

RALPH IRWIN HENDERSON, OF CHARLESTON, WEST VIRGINIA.

FISHING TOOL.

Application filed June 14, 1928. Serial No. 285,440.

This invention aims to provide a simple means for gripping tools and the like which are to be fished out of a well, and, in particular, the invention aims to provide a novel 5 means for resetting the tool.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 15 and claimed, it being understood that changes in the precise embodiment of the invention herein disclosed, may be made within the scope of what is claimed, without departing from the spirit of the invention.

20 In the accompanying drawings:-

Figure 1 is a longitudinal view of a tool constructed in accordance with the invention, parts being in section;

25 Figure 2 is a transverse sectional view showing the lower end of the spider or carrier, and attendant parts;

Figure 3 is a bottom plan of the spider;

30 Figure 4 is a fragmental longitudinal section showing a portion of the stem and part of the latch.

The tool forming the subject matter of this application comprises a body 1, made up of two parts, namely a head 2 and a stem 3 threaded at 4 into the head. The head 2 is supplied with any preferred means 5 whereby it may be connected to a drilling stem (not shown), a string of pipe (not shown), or anything else whereby the tool may be raised and lowered in a well. On the lower end of the stem 3, a foot is fixed, and the foot, as a whole, is marked by the numeral 8. It comprises a conical part 6 having its smaller end downward, the foot 8 having a cylindrical part 7 at the upper end of the cone 6. There is a mark 9 on the edge of the cylindrical upper end 7 of the foot 8.

50 The stem 3 is provided with an encircling groove located above the foot 8, and the groove, throughout the major portion of its length is spiral, as shown at 10. The upper part 10^a of the groove makes a complete turn at right angles to the axis of the stem, and the lower part 10^b of the groove makes a half turn at right angles to the axis of the stem. The spiral groove 10 forms a spiral

rib 11. The upper edge of the rib 11 is undercut as shown at 12, to form a seat. A closer 14 is counted on the stem 3, and has its smaller end uppermost. The closer 14 is not secured to the stem 3, but in practice the 60 closer maintains a substantially fixed position on the stem, the closer being pushed upwardly into abutment with the lower end 15 of the head 2, by a compression spring 25 which will be alluded to hereinafter.

65 A spider or carrier 16 is mounted to slide up and down on the stem 3, and to rotate on the stem, the spider being located between the foot 8 and the closer 14, the spider having a bore 17 in which the stem 3 is received. The 70 spider 16 carries a projection, in the form of a pin 50, which is extended into the groove of the stem 3. On the lower end of the spider 16 there is a mark 26, shown in Figure 2, this mark being adapted to cooperate with the mark 9 on the edge of the part 7 of the foot 8, for a purpose which will be described hereinafter. There are longitudinal slots 18 in the spider 16, the slots being adapted 75 to receive gripping levers 19.

80 There may be as many of the slots 18 and of the levers 19 as is desired, three levers being shown in the present instance. At their lower ends, the levers 19 are supplied with gripping jaws 20. The levers are fulcrumed intermediate their ends on pivot elements 21 mounted in the spider or carrier 16, the part 16 being alluded to as a carrier because it carries the gripping levers 19. At their upper ends, the levers 19 are equipped with inwardly 85 extended projections 22 adapted to ride lengthwise on the conical closer 14. Intermediate their ends, the levers 19 are supplied with inwardly extended projections 23, adapted to rest against the cylindrical part 7 90 of the foot 8 and to ride up and down on the conical part 6 of the foot.

95 A cup shaped member 24 is mounted on the stem 3 above the spider or carrier 16. The said member 24 is not fixed to the spider 16, 100 but is pressed downwardly against the upper end of the spider 16 by a compression spring 25 mounted on the stem 3. The spider 16 has a transverse opening 27 which is reduced at its inner end as shown at 28, to form a shoulder 105 29. A plug 30 is threaded into the spider 16 at the outer end of the opening 27 and may be considered as a part of the spider. A latch 31, in the form of a pin, is mounted for slid- 110

opening 27, the latch 31 having an enlarged head 33 located in the opening 27.

The latch 31 has a conical inner end 32 adapted to engage in the undercut seat 12 at the upper edge of the spiral rib 11 on the stem 3. A compression spring 34 is located in the opening 27 and surrounds the latch 31. The spring 34 presses at its inner end against the shoulder 29, and at its outer end against the head 33. A seating member is provided, the same preferably being in the form of a screw 35 threaded into the plug 30 and adapted to engage the head 33 of the latch 31.

When the tool is ready to be lowered into the well, the parts are arranged as shown in Figure 1. When the tool has arrived at the place of use, down in the well, the lower ends of the levers 19 touch the object which is to be fished out. The weight of the device by which the tool is lowered causes the stem 3 to move down a little in the spider, so that the undercut seat 12 on the spiral rib 11 of the stem 3 is moved clear of the conical end 32 of the latch 31. The latch 31 now moves to the right in Figure 1, under the action of the spring 34.

The body 1 is raised a fraction of an inch or so to set the lower ends of the levers 19 free of contact with the object in the bottom of the well, and this permits the compression spring 25 to begin its work, the spring 25 sliding the spider 16 and the levers 19 downwardly. As the spider and the levers move downwardly, the projections 23 ride downwardly on the cone 6, and the projections 22 ride downwardly on the cone 14, the jaws 20 being closed on the object. The heavier the object, the tighter will the jaws 20 be closed upon it, since as the carrier or spider 16 is pulled downwardly by the weight of the object, the projections 22 tend to ride further downwardly on the conical closer 14.

When it is desired to reset the tool, the spider 16 is rotated on the stem 3 until the mark 26 on the spider registers with the mark 9 on the foot 8. This insures that the lower half-turn 10^b of the groove 10 is in such a position that the inner end 32 of the screw 35 can be engaged in 11 when the screw is advanced. The screw 35 is threaded into the plug 30, and the latch 31 is advanced until the inner end 32 of the latch is engaged in the lower end 10^b of the groove, and with the undercut seat 12. The reason for having the part 10^a of the groove in the stem at right angles to the axis of the stem is to prevent the inner end 32 of the latch 31 from moving down along the spiral part 10 of the groove responsive to the pressure exerted by the spring 25. When the spider 16 is rotated on the stem 3, the spider will move upwardly on

the stem until the end 32 of the latch 31 engages the stop pin 50. The spring 25 thus is put under compression, and the conical opener 6 cooperates with the projections 23 to spread the jaws 20 apart. The parts now are in the position shown in Figure 1, the screw 35 is removed, and the tool is set and ready to be lowered into the well again.

What is claimed is:—

1. In a fishing tool for use in wells, a stem having a spiral rib, a carrier mounted to slide upwardly and downwardly on the stem, spring means cooperating with the carrier to slide it downwardly, gripping members movably mounted on the carrier, means for closing the gripping members when the carrier slides downwardly on the stem, responsive to the spring means, a latch movable on the carrier and engageable with the rib to hold the carrier against downward movement responsive to the spring means, mechanism for disengaging the latch from the rib when the downward movement of the carrier is arrested as the tool arrives at the place of use in the well and when the stem moves downwardly with respect to the carrier, the carrier being rotatable on the stem whilst the latch is engaged with the spiral rib, thereby to move the carrier upwardly on the stem and to compress the spring means.

2. In a fishing tool for use in wells, a stem having a spiral rib, a carrier mounted to slide upwardly and downwardly on the stem, spring means cooperating with the carrier to slide it downwardly, gripping levers fulcrumed intermediate their ends on the carrier, an upper cone on the stem above the carrier, and having its smaller end uppermost, a lower cone on the stem below the carrier and having its smaller end lowermost, the lower cone constituting an opener for the levers when the carrier moves upwardly with respect to the stem, and the upper cone constituting a closer for the levers when the carrier moves downwardly with respect to the stem, a latch movable on the carrier and engageable with the rib to hold the carrier against downward movement responsive to the spring means, mechanism for disengaging the latch from the rib when the downward movement of the carrier is arrested as the tool arrives at the place of use in the well and when the stem moves downwardly with respect to the carrier, the carrier being rotatable on the stem whilst the latch is engaged with the spiral rib thereby to move the carrier upwardly on the stem and to compress the spring means.

In testimony that I claim the foregoing as my own, I have hereto affixed my signature.

RALPH IRWIN HENDERSON.
